UNITED STATES PATENT OFFICE.

ERNST MÖGEL, OF MEISSEN-ON-THE-ELBE, GERMANY, ASSIGNOR TO THE FIRM AKTIENGESELLSCHAFT FÜR CARTONNAGENINDUSTRIE, OF DRESDEN, GERMANY.

APPARATUS FOR THE GROOVING OF CARDBOARD.

Application filed November 2, 1927, Serial No. 230,611, and in Germany November 4, 1926.

This invention relates to novel apparatus for the grooving of cardboard, including corrugated cardboard, and is characterized by the feature that the groove (compare Fig. 1) is produced by drawing the sheet of cardboard through an implement formed by three blades. Inasmuch as the blades form a passage of definite profile, through which the cardboard is drawn, it may be compared with a draw plate for the drawing of profiled wires, except for the fact that in the case of the present invention the blades form a gradually narrowing passage. It is just in this gradual narrowing of the passage, however, that the advantage of the new apparatus consists, as compared with the grooving appliances with rollers that are otherwise customary. In these known appliances, on account of the curvature of the operating rollers, the cross-sectional area of passage tapers so rapidly that the cardboard is constrained to acquire the channel-shaped profile too quickly, or in other words on too short a path, which involves heavy stressing of the cardboard and very great resistance to the work. In the new apparatus the tapering or narrowing of the profile formed by the blades can be distributed over as long a tract as may be desired, with gradual formation of the groove, which in the case of a roller groover, would only be possible with rollers of excessively large diameter, which in practice would be inadmissible on account of the space occupied.

The apparatus according to the invention may be constructed in various forms. For the treatment of cardboards which are always of the same thickness the three blades may be undisplaceable in relation to one another, and two of them, which will hereinafter be referred to as the upper blades, may be united to form a single body. In most cases, however, the blades will be made relatively adjustable, so as to enable cards of different thicknesses to be treated and to enable the groove to be more or less sharply impressed as desired. The third blade, hereinafter briefly referred to as the lower blade, may if desired be formed by a chain running over chain wheels and supported between the chain wheels by a sliding surface, this chain moving with the cardboard, and having

longitudinal ribs on the back of the links, which collectively form the lower blade.

In the accompanying drawing, ⁵⁵ Figure 1 shows the piece of cardboard P, with a groove p being produced by the apparatus according to the invention,

Figure 2 is a side elevation, and

Figure 3 is a front elevation of one constructional form, while

Figure 4 is a side elevation, and

Figure 5 is a front elevation of a further constructional form.

In most cases it is a question of producing ⁶⁵ a number of parallel grooves simultaneously in the sheet of cardboard. There will therefore usually be a plurality of the devices hereinafter described on one machine, and these will be arranged in such a way that the individual devices are adjustable as regards their distances from one another. In the drawings only a single device is illustrated.

Extending transversely across the machine there are two shafts 1 and 2 of large diameter, which are driven in the direction of the arrow at the same velocity, and which carry, for each individual device, a roller or disc, 3 and 4 respectively. The rollers 3 and 4 co-operate with rollers 5 and 6, which are ⁷⁰ journaled in forked holders 7 and 8. These holders are vertically and transversely adjustable in transverse frame beams 9 and 10. They are adjustable in height for the purpose of enabling them to be adjusted according to ⁷⁵ the thickness of the cards to be treated; and they are transversely displaceable, as are also the rollers 3 and 4, for the purpose of enabling them to be adjusted to the appropriate distance from the adjacent devices. For the ⁸⁰ roller 5 an additional special adjusting means is provided for the accurate settlement of its height in relation to the upper blades. The centre part of a bolt 11, upon which the roller 5 rotates, is eccentrically offset relatively to the end parts of the bolt located in the fork 7, so that by rotating the bolt the height of the roller axis is altered. For the ⁸⁵ purpose of the adjusting, the bolt head 12 is formed as a worm wheel, with which there ⁹⁰ engages a worm 13, rotated by a handle 14.

The two pairs of rollers, the upper members of which are driven by friction against the cardboard P, serve in the first place for con-

veying the cards through the grooving apparatus in the direction of the arrow in Fig. 2. The front pair of rollers, 3 and 4, serves however at the same time to compress the cardboard at the position where the groove is to be produced, by laterally crowding together the material, which then assumes the arched form shown at p' in Fig. 3. By virtue of this pressing, even corrugated cardboard can be grooved, because the corrugations are pressed down in the neighbourhood of the grooves to be produced. The roller 4 is provided with an encircling rib 4', which, in co-operation with the roller 6, which is provided with a corresponding groove 6', completes the formation of the groove in the manner of an ordinary roller groover. The apparatus according to the invention may, however, be constructed in combination with ordinary rollers, that is, merely conveying rollers.

The actual implements for the grooving of the cardboard consist of two upper blades 15 and 16, and a lower blade 17. The two upper blades are inclined towards the right in Fig. 2 and overlap the lower blade 17, which in plan lies between them, so that the cardboard, upon passing between the three blades, is depressed on both sides of the lower blade and is pressed against the sides of the lower blade, whereby it gradually assumes a profile of the shape shown in Fig. 1. It will be understood that the lower blade has the form of a rib similar to the rib 4' on the roller 4, while the upper blades are in the form of ledges or strips, as shown in Fig. 3. In order to enable the two upper blades to be adjusted relatively to one another the strips 18 and 19 are constructed towards the top as levers, which are rockable about bolts 20 and 21 in the holder 7. The upper ends of the levers are formed as segments of worm wheels 22 and 23, in which there engage worms 24 and 25, the threads of which run in opposite directions, upon a transverse shaft 26. By means of a worm wheel 27 on this shaft and a worm wheel 28 on a shaft 29, with a handle 30, the shaft 26, with the two worms, can be rotated, in which case the upper blades 15 and 16 are rocked either towards the lower blade 17 or away from the latter, according to the direction of rotation.

In the second constructional form, illustrated in Figs. 4 and 5, instead of the stationary lower blade 17 there is a chain consisting of links 17^a having ribs 17^b of the same form of profile as the fixed blade 17. The chain runs over chain wheels 31 and 32 and is supported between the two chain wheels, by a stationary gliding surface 33. 34 is a guiding and tensioning roller for the chain. The chainwheels are mounted between the halves of two-part rollers 3^a and 4^a. The roller 5^a has a recess 5^b turned in it, as

shown in Fig. 5, and the roller 6^a, with a groove 6^b, corresponds to the roller 6' of the first constructional example. The arch p' of the cardboard P may be produced by a special pair of rollers, not shown, or the cardboard may be introduced between the rollers 5^a and 3^a without any such preparation.

What I claim is:—

1. Apparatus for the grooving of cardboard, including corrugated cardboard, comprising three blades so placed as to form a gradually tapering channel-shaped passage, and rollers for drawing the cardboard through said passage so that two of the blades bear against it on one side and the other on the other side, at a position between the first two blades.

2. Apparatus for the grooving of cardboard, including corrugated cardboard, comprising three blades so placed as to form a gradually tapering channel-shaped passage, rollers for drawing the cardboard through said passage so that two of the blades bear against it on one side and the other on the other side, at a position between the first two blades, and means for varying the distance apart of the two blades that act on the same side of the cardboard.

3. Apparatus for the grooving of cardboard, including corrugated cardboard, comprising three blades so placed as to form a gradually tapering channel-shaped passage, rollers for drawing the cardboard through said passage so that two of the blades bear against it on one side and the other on the other side, at a position between the first two blades, and means for varying the distance of the two blades that act on the same side of the cardboard from the other blade.

4. Apparatus for the grooving of cardboard, including corrugated cardboard, comprising three blades so placed as to form a gradually tapering channel-shaped passage, rollers for drawing the cardboard through said passage so that two of the blades bear against it on one side and the other on the other side, at a position between the first two blades, means for varying the distance apart of the two blades that act on the same side of the cardboard, and means for varying the distance of the two blades that act on the same side of the cardboard from the other blade.

5. Apparatus for the grooving of cardboard, including corrugated cardboard, comprising a carrier, means for adjusting the height of said carrier, two blades fitted to said carrier and adapted to bear against one side of the cardboard, the acting edges of said blades being substantially parallel to one another, a third blade arranged between said parallel blades and adapted to bear against the other side of the cardboard, the plane containing the edges of the

parallel blades being clear of the third blade at one end but intersecting it at a small angle at an intermediate point, and rollers for drawing the cardboard between said blades.

6. Apparatus for the grooving of cardboard, including corrugated cardboard, comprising a carrier, means for adjusting the height of said carrier, two blades pivotally mounted on said carrier and adapted to bear against one side of the cardboard, the acting edges of said blades being substantially parallel to one another, means for rocking said blades transversely about their pivots in opposite directions to vary the distance between their acting edges, a third blade arranged between said parallel blade and adapted to bear against the other side of the cardboard, the plane containing the edges of the parallel blades being clear of the third blade at one end but intersecting it at a small angle at an intermediate point, and rollers for drawing the cardboard between said blades.

7. Apparatus for the grooving of cardboard, including corrugated cardboard, comprising a carrier, means for adjusting the height of said carrier, two blades pivotally mounted on said carrier and adapted to bear against one side of the cardboard, the acting edges of said blades being substantially parallel to one another, means for rocking said blades transversely about their pivots in opposite directions to vary the distance between their acting edges, said means comprising worm wheel sectors formed on said blades, a transverse shaft, and two oppositely threaded worms secured to said shaft and meshing with said worm wheel sectors, and a third blade arranged between said parallel blades and adapted to bear against the other side of the cardboard, the plane containing the edges of the parallel blades being clear of the third blade at one end but intersecting it at a small angle at an intermediate point, and rollers for drawing the cardboard between said blades.

8. Apparatus for the grooving of cardboard, including corrugated cardboard, comprising a carrier, two blades fitted to said carrier and adapted to bear against one side of the cardboard, the acting edges of said blades being substantially parallel to one another, a pair of chain wheels, a chain passing round said chain wheels, a longitudinal rib on each link of said chain, said ribs combining to form a third blade arranged between said parallel blades and adapted to bear against the other side of the cardboard, a stationary supporting surface over which the chain glides and which is adapted to hold said chain in such a position that the plane containing the edges of the parallel blades is clear of the third blade at

one end but intersects it at a small angle at an intermediate point, and rollers for drawing the cardboard between said blades.

9. Apparatus for the grooving of cardboard, including corrugated cardboard, comprising a carrier, a unitary body comprising two blades fitted to said carrier and adapted to bear against one side of the cardboard, the acting edges of said blades being substantially parallel to one another, 75 a third blade arranged between said parallel blades and adapted to bear against the other side of the cardboard, the plane containing the edges of the parallel blades being clear of the third blade at one end but intersecting it at a small angle at an intermediate point, and rollers for drawing the cardboard between said blades.

10. Apparatus for the grooving of cardboard, including corrugated cardboard, comprising a carrier, two blades fitted to said carrier and adapted to bear against one side of the cardboard, the acting edges of said blades being substantially parallel to one another, a third blade arranged between 80 said parallel blades and adapted to bear against the other side of the cardboard, the plane containing the edges of the parallel blades being clear of the third blade at one end but intersecting it at a small angle at an intermediate point, rollers for drawing the cardboard between said blades, 85 and rollers for feeding the cardboard towards said blades, one of said feeding rollers having a convex rim and the other a concave 90 rim, so as to arch the cardboard before it reaches the grooving blades.

11. Apparatus for the grooving of cardboard, including corrugated cardboard, comprising a carrier, two blades fitted to said 105 carrier and adapted to bear against one side of the cardboard, the acting edges of said blades being substantially parallel to one another, a third blade arranged between said parallel blades and adapted to bear against the other side of the cardboard, the plane containing the edges of the parallel blades being clear of the third blade at one end but intersecting it at a small angle at an intermediate point, rollers for drawing the cardboard between said blades, a circumferential 110 rib on one of said rollers, and a corresponding circumferential groove on the other, said rib and groove being adapted to complete the grooving of the cardboard.

12. Apparatus for the grooving of cardboard, including corrugated cardboard, comprising a carrier, two blades fitted to said carrier and adapted to bear against one side of the cardboard, the acting edges of said blades being substantially parallel to one another, a pair of chain wheels, a chain passing round said chain wheels, a longitudinal rib on each link of said chain, said ribs combining to form a third blade ar- 125

ranged between said parallel blades and adapted to bear against the other side of the cardboard, a stationary supporting surface over which the chain glides and which is 5 adapted to hold said chain in such a position that the plane containing the edges of the parallel blades is clear of the third blade at one end but intersects it at a small angle at an intermediate point, rollers for drawing the cardboard between said blades, and a circumferential groove on the drawing roller which is on the same side of the cardboard as the two grooving blades, said groove being adapted to co-operate with the ribs on the chain links to complete the 15 grooving of the cardboard.

In testimony whereof I have signed my name to this specification.

ERNST MÖGEL.
